(57) **CLAIM**

The ornamental design for a portable cooler and heater, as shown and described.

DESCRIPTION

FIG. 1 is a first perspective view of a portable cooler and heater showing our new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1; and,

FIG. 10 is an enlarged view of the selected portion 10 in FIG. 1.

The broken lines shown in the drawings depict portions of the portable cooler and heater that form no part of the claimed design. The dot-dash broken lines in FIGS. 1, 9 and 10 represent the boundary of the enlarged portion and form no part of the claimed design.
